UNITED STATES PATENT OFFICE.

JOHN O. ALMEN, OF SEATTLE, WASHINGTON, ASSIGNOR TO ALMEN-CROSBY MOTORS COMPANY, INC.

VALVE MECHANISM FOR INTERNAL-COMBUSTION ENGINES.

Application filed August 10, 1920. Serial No. 402,565.

This invention relates to improvements in internal combustion engines, and more particularly to improvements in rotating valve mechanism and parts associated therewith for the distribution of fuel charges to, and their discharge from the explosion chambers of an internal combustion engine wherein a plurality of cylinders are arranged in circular relation about, and parallel with a centrally disposed power shaft, and wherein the valve rotates in a plane perpendicular to the shaft and is driven by a certain geared connection therewith that advances the valve to effect the intaking, and discharge of fuel charges for the several cylinders in the proper sequence to effect operation of the engine.

The principal object of the present invention is to provide a rotating valve mechanism which controls intaking and exhausting of fuel charges from the cylinders of the engine and which will be maintained sufficiently cool for successful operation by the passage therethrough of the intaken charges; also, to provide for better distribution of fuel charges to the several cylinders of the engine; to insure even wear and lubrication; to give an even balance to the mechanism and to provide for the complete scavenging of burned fuel charges from about the sparking points after each explosion.

In accomplishing the objects of the invention I have provided the improved details of construction, the preferred forms of which are illustrated in the accompanying drawings, wherein—

Figure 1 is a longitudinal sectional view embodying valves and actuating mechanism constructed in accordance with the present invention.

Figure 2 is a transverse sectional view through the valve casing, showing the relation of the control valve to the distributing manifold.

Figure 3 is a face view of a rotating valve.

Figure 4 is a central sectional view of the same, taken in a plane parallel with its face.

Figure 5 is a fragmental sectional view taken on the line 5—5 in Figure 3 illustrating the disposition of the relief opening for the outlet of burned gas from the sparking chamber.

Figure 6 is a sectional view on the line

6—6 of Figure 1, illustrating the gearing for driving the valve member from the power shaft.

Figure 7 is an end view of the engine casing.

Figure 8 is an enlarged sectional view transversely through the rotating valve and casing head.

Figure 9 is a detail perspective view of an electric contact member. Referring more in detail to the several views of the drawings wherein like reference numerals designate like parts—

1 and 2 designate complemental housings or cylinder casings, each of which embodies a plurality of cylinders 3 wherein pistons 4 are operative, mounted for reciprocation. The two casing sections are joined together by bolts 5 extended through peripheral flanges 6 formed their adjacent ends, which retain the corresponding cylinders of the two sections in functional alinement.

Extending centrally, and longitudinally through the engine casing, is a power shaft 8, which is supported, adjacent its opposite ends, within bearings 9 and 10 that hold it revolvably in position. Formed centrally on the shaft, is a journal 12, the axial line of which bisects the axial line of the shaft at an acute angle, and mounted revolvably on the journal is a rocker head 14 which serves as the medium through which driving energy is transmitted to the power shaft from the several pistons, as is more fully described in my co-pending application Ser. No. 163,561.

By reason of mounting the rocker head on an inclined journal of the shaft, reciprocation of the pistons in proper order will impart a certain wabbling motion to the head which in turn effects rotation of the power shaft.

Each cylinder is provided at its outer end with a single port 21; serving for both gas inlet and outlet purposes and the several ports are arranged circularly about the power shaft 8 and are in alinement with exhaust openings 23 in the end heads 24 of the casings.

To regulate the flow of gases in both directions, I provide each end of the engine with a rotating valve 25 of a special character and these valves are interposed between the cylinder end walls 20 and the casing heads 24, and are operated by connec-

tion with the power shaft in such manner as to control the intaking and exhausting of fuel charges from the various cylinders.

In shape, each valve is circular, and is provided centrally with an opening for receiving the concentric sleeve 26 of a gear pinion 28 Figure 8, which is secured fixedly to the valve by means of a series of bolts 29. The pinions for the two valves are provided with central bores whereby they are revolvably mounted on eccentric journals 30 formed on the power shaft, and are adapted to travel in mesh with somewhat larger internally toothed ring gears 31 that are fixed in the ends of the cylinder casings concentric with the power shaft.

The eccentrics 30, one for the valve at each end of the engine, are disposed with their axes at opposite sides of the shaft axis, so that the centrifugal force of the mass of the respective valves due to their motion about the shaft axis will be applied to act counter to the unbalanced moments due to the reciprocation of the various pistons with respect to the shaft axis.

It will be seen that rotation of the crank shaft 8 will cause successive teeth of the valve gear 28 of each valve to come into mesh with the teeth of its respective internal gears 31, and since the valve gears 28 contain a lesser number of teeth than the internal gears, a rotary motion will be imparted to the valves, while at the same time they will be moved bodily, circularly about the shaft.

By such gears, the valves are caused to be rotated while being carried about the axis of the shaft, with a succession of epicycloidal movements being imparted thereto.

The valves are operable in recesses 34 in the engine ends, and seat against wearing, or packing, plates 35 on their inner faces, and at their outer faces against the adjacent casing heads 24 which have the discharge openings 23 in alinement with the cylinder ports. These discharge openings 23 may, if desired be connected with a suitable exhaust manifold not shown in the drawings.

The packing plates 35 are provided with ports in registration with the cylinder ports, but the valve members in an engine having the number of cylinders shown in the illustrated embodiment, are provided with three similar and symmetrically located channels 38 for the intaking of gases into the cylinders and have three passages 39 placed intermediate the inlet channels for the exhaustion of gases; said exhaust passages being located so as to register, upon occasion, with the cylinder ports, subject to the epicycloidal movement of the valves.

The recesses, wherein the valves operate, are circular and are of greater diameter than the valves, and have fitted concentrically therein rings 40 which form annular

manifolds 41 about the valves into which the fuel gases are admitted from an inlet manifold 42 and from which this fuel is distributed to the valve through a plurality of openings 43; the latter openings being equally spaced apart and have a total area equal to the area of the inlet opening of the inlet manifold so that there will be an equal distribution of fuel to all sides of the valve.

The disposition of the exhaust openings through the valve and the character and disposition of the inlet channels is such that the intaken charges will act as a cooling medium for the valve. In the present construction, the valve members are not solid, but may be termed shell construction, having opposite face plates that are spaced apart by the walls of the inlet and exhaust channels. The exhaust passages are spaced at equal angular distances about the periphery of the valve, and the inlet channels 38 lead from the edge of the valve inwardly, and then in an outward direction to their inlet openings in the inner face of the valves in such manner as to partially surround or inclose the exhaust passages. Such a disposition of inlet channels and exhaust passages in connection with the disposition of the valves within the distributing manifold insures not only an even distribution of fuel charges to the cylinders but also an effective method of retaining the valves at an operating temperature, due to the circulation of the intaken charges about the exhaust passages.

Each of the exhaust passages through the valve is inclosed by a wall 44 of thin metal not formed as a part of the valve body, against which the exhausted charges are directed. These lining walls prevent the exhausted charges from coming into direct contact with the main valve structure and, since they are spaced from the latter, provide dead air spaces about the passages which serve as insulating mediums. The exhaust passages are each divided by a plurality of partitions 44' directed radially of the valve and transversely to the direction of movement and which serve as means for causing the exhaust charges to pass directly through and thus eliminate the eddying of charges within the passages at times when they are not entirely in registration with the cylinder ports, that is, at times when the passages are partially overlapping the cylinder ports.

The speed and direction of rotation, and number of openings in the valve follow certain definite laws. In this engine containing seven cylinders, three sets of ports are employed and the valve is rotated at one sixth of the crank shaft speed in the opposite direction thereto. It will be seen that definite divisions on the valve correspond in time and position to the piston strokes, that

is, the part of the valve containing the intake passages will always be passing a cylinder port as a piston in that cylinder is moving on its in stroke, the part containing the exhaust passage passes a cylinder port on the out stroke of its piston, and a face portion of the valve will be moving across the cylinder port during an expansion stroke. For these reasons, three points on the valve 10 midway between the exhaust and intake passage measured on the long arc, always present themselves at a cylinder port at the time when the piston in that cylinder has completed the compression stroke and is ready to fire. If, therefore, spark plugs be placed in the valve at these points and caused to spark at the proper time, then only three plugs will be needed to serve the seven cylinders, and since they move with the valve, they are exposed to only a relatively small amount of heat, for they are present in the heat of combustion for a short period of time only and then move off to a comparatively cool position, thus avoiding a common 15 20 25 source of trouble.

Referring particularly to Figures 4 and 8, 50 designates spark plugs that are mounted in radially directed pockets 51 in the valve body; said pockets being provided with 30 openings 52 which, during operation of the valve, move successively into communication with the cylinder ports.

One of the terminals of each plug may be grounded through the engine frame, and the others extended from the inner ends of the plugs to engage the yieldable legs 53 of contact plates 54, that are fixed at equally spaced distances to the outer side of annular, insulating rings 56, secured concentrically within the valves.

Each of the plates 54 has a yieldable prong 57 extended outwardly therefrom and these prongs are engageable at certain times during operation of the valve, with an electric conducting ring 58 secured in the end head of the engine concentric with the power shaft, as is shown especially in Figure 8, and which is electrically connected by a terminal post 59 with an electric circuit, which latter is completed through the engine casing.

The several spark plugs and contact members are so arranged and located, that ignition sparks will be produced by the plugs as they pass in registration with the cylinder ports.

In order to avoid in-efficiency due to the pocketing of burned gases after each explosion, in the spark plug chambers, I have provided each of these chambers with discharge ports 60, as is best shown in Figure 5, which move after their respective spark plugs have ignited a charge, into communication with a discharge port in the engine head so that the burned gas, confined under pressure in these chambers, may be exhausted before the

plug again moves into registration with a cylinder port.

In operation of the engine, the explosive mixture is supplied by suitable intake manifolds to the circular manifolds 40 in the opposite end heads of the casing and, subject to the control of the valves 25, it is delivered through the channels 38 to the various cylinders. 70

After the manner of operation of four stroke cycle engines, the charges are admitted into the cylinders during the suction stroke of their pistons, compressed during the following reverse strokes, then exploded in the third strokes to impel the pistons which, in the fourth stroke, effect the discharge of the spent gases through the various valve passages 39 and from the engine. 75 80

The reciprocation of the pistons acts, through the medium of the rocker head, to rotate the drive shaft, and this through the eccentrics 30 will cause successive teeth of the valve gears 28 to be brought into mesh with the teeth of the internal gears 31, and since, in the present construction, the valve gears contain forty-eight teeth and the fixed ring gear contains 56 teeth, a rotary motion will be imparted to the valves which is opposite to the direction of rotation of the shaft and at one sixth its speed. 85 90 95

Assuming then that the drive shaft is rotating in a clockwise direction and the valve is rotating in a counterclockwise direction, with the valve in the position it assumes relative to the several cylinder ports which in Figure 4 I will designate individually by letters *a*, *b*, *c*, *d*, *e*, *f*, *g* and the spark plugs by the letters *S*, *T*, *Z*; the spark plug *S* at the lower side of the figure is in position to fire the charge in the cylinder *a* with which 105

it registers. After the shaft has moved in a clockwise direction six-sevenths of a revolution this plug will have been moved in a counterclockwise direction a distance equal to one-seventh of a revolution which will bring it into registration with the cylinder *g*, but before it reaches this cylinder, the spark plugs *T* and *Z* will have moved into firing relation with the cylinder *c* and *e* to fire these in regular order. Again after six-sevenths of a revolution of the whole crank shaft after the plug *S* had fired the cylinder *g*, this plug would be brought by movement of the valve into registration with the cylinder *f* but during its movement between the

f, a, etc. which will cause the crank shaft to be driven in a clockwise direction.

Since the firing of any cylinder takes place at the time when the valve has been moved 5 by the eccentric on which it rotates to its limit in the direction of that cylinder, it will be seen that the yieldable prongs 57 of the contact plate 54 with which the spark plugs have individual electrical contact connection, 10 will at that time be brought into engagement with the fixed contact ring 58 to complete the electrical connection through the plug. The prongs are made yieldable in order that they will contact the ring 58 before, and re- 15 main in contact a short interval after each epicycloidal movement of the prong and valve relative to the ring to allow for the advancing or retarding of the spark by the use of suitable timing mechanism which 20 would be located in the circuit and is not herein shown.

After a contact 57 has caused the firing of any particular cylinder of the engine, it moves away from the ring 58, due to its par- 25 ticular epicycloidal movement, and does not again contact the ring until after six- sevenths of a revolution of the crank shaft. The movement of the point—57a—is illus- 30 trated by the course of the dotted line in Figure 7.

It will also be noted by reference to Figures 1, 2 and 4, that at the time when any particular cylinder is intaking a charge of fuel, the rotating valve will be moved to its 35 limit toward the opposite side of the valve recess wherefrom this fuel charge is being drawn, thereby providing a channel of maximum volume leading up to the inlet channel.

What I claim is:

40 1. In an engine comprising a casing forming an annular valve recess, a rotary valve mounted in the recess and of smaller diameter than the latter to provide an annular manifold between the two; said valve having 45 passages for delivering exhaust gases from the engine and having circuitous inlet channels therein opening into the manifold and enclosing the exhaust passages.

2. A rotary valve for internal combustion 50 engines comprising a body having exhaust openings therethrough and having inlet channels arranged alternately with and ex- tended to partially surround the exhaust openings and which are adapted for con- 55 tinuous communication at their outer ends with a fuel supply manifold and at their inner ends open to the inner face of the valve and are adapted to be moved alternately

with the exhaust openings into and from registration with ports communicating with the cylinders of the engine. 60

3. In an engine of the character described, a power shaft having an eccentric journal, a valve rotatably mounted on the journal and operable to control the intaking and exhaust- 65 ing of fuel charges, an internal gear ring fixed concentric about the shaft, a gear fixed to the valve concentric thereto and to the journal and operable within the ring gear to 70 revolve the valve with an epicycloidal movement in a direction opposite to the direction of the shaft.

4. A rotary valve of the character de- 75 scribed having a spark plug chamber open- ing at one side thereof adapted to be brought by rotation of the valve into and from registration with the cylinders of the engine wherein the valve is used and means for per- 80 mitting the scavenging of burned charges from the spark plug chamber at times when it is not in communication with the cylinder.

5. A rotary valve for internal combustion engines provided with a spark plug chamber having an opening leading to one side thereof adapted to be brought, by movement of 85 the valve, into and from registration with the explosion chambers of the engine wherein the valve is used and having a scavenging opening leading to the opposite side of the valve for the purpose set forth. 90

6. A circular rotating valve for an internal combustion engine of the class described comprising a valve body with openings therethrough for the exhausting of fuel charges from the cylinders of the engine 95 wherein the valve is used, and partitions dis- posed in said openings radially of the cir- 100 cular valve.

7. In an engine of the character described, in combination, an engine casing comprising 100 a plurality of cylinders and forming an annular valve recess, each of said cylinders having a single port opening into said re- 105 cess, a circular valve of smaller diameter than the recess mounted for rotation therein and having fuel inlet openings leading from 110 its periphery inwardly to pass in registration with the cylinder ports, and an annular fuel distributing manifold surrounding the valve and having openings therein at spaced intervals for admitting fuel gases to the valve recess for the purpose set forth. 115

Signed at Seattle, Washington, this 4th day of August, 1920.

JOHN O. ALMEN.
